UNITED STATES PATENT OFFICE.

WILLIAM GEPFORD, OF WEST SALEM, OHIO.

FENCE-POST.

SPECIFICATION forming part of Letters Patent No. 366,578, dated July 12, 1887.

Application filed April 14, 1887. Serial No. 234,814. (No model.)

To all whom it may concern:

Be it known that I, WILLIAM GEPFORD, a citizen of the United States of America, residing at West Salem, in the county of Wayne 5 and State of Ohio, have invented certain new and useful Improvements in Fence-Posts; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 My invention relates to certain new and useful improvements in fence posts; and it consists in the construction and combination of the parts, as will be hereinafter fully set forth, and specifically pointed out in the claims.

20 In the accompanying drawings, which illustrate my invention, Figure 1 is a vertical section of a fence post and support constructed in accordance with my improvement, and Fig. 2 is a detail perspective view of the base or 25 post-support.

30 A refers to the post proper, which is made of pipe, which is formed of suitable material, as clay or metal, and to said pipe or tube is attached by bolts *a a*, which pass through suitable perforations therein, a vertical strip, *A'*, of wood, which is provided at intervals with eyebolts *a'*, to which wires can be secured. Instead of eyebolts, planks may be secured to this wooden strip *A'* by nails.

35 B refers to the base, which is preferably made of iron, and consists of a circular upwardly-projecting portion, *b*, which is formed integral with the bifurcated portion beneath the same. The lower portion of this base, adjacent to the projecting portion *b*, has a horizontal portion, *C*, from which depend arms *d*, said arms being parallel with each other. The lower portions of these arms are provided with bolt-holes, through which pass a bolt, *e*, which 40 serves to retain the anchor-plates *D* in place.

These anchor-plates *D* consist of strips of wood, which are recessed, as shown, so as to extend above the lower edge of the transverse portion *C*, and when the bolt is inserted beneath these anchor-plates they will be held 50 firmly in position.

In constructing the fence the anchor-plates are first secured to the base plate by the bolt *e*, and a hole is dug in the ground of sufficient depth, and the earth is packed firmly around 55 the anchor-plates *D* and the base *B* to a line with the upper edge of the horizontal portion *C*. The post *A* is then slipped over the projecting portion *b*, which will serve to hold the same securely in a vertical position, and the 60 earth is then placed around the base of the post.

By the construction hereinbefore described I provide a means for holding the post securely in a vertical position, and which will permit 65 the removal of said post when desired.

I claim—

1. In combination with a tubular fence-post, the metallic base piece or support having an upwardly-projecting portion, *b*, and 70 transverse portion *C*, which forms shoulders adjacent to the upwardly-projecting portion, and depending portions *d*, with bolt-holes at their lower ends, and anchor-plates *D*, having their upper edges recessed, substantially as 75 shown, and for the purpose set forth.

2. The combination, substantially as described, of the bifurcated base provided with an upwardly-projecting tenon, the anchor secured to the legs of the base, and a fence-post 80 provided at its lower end with a socket constructed to fit snugly upon the tenon of the base.

In testimony whereof I affix my signature in presence of two witnesses.

WILLIAM GEPFORD.
